UNITED STATES PATENT OFFICE.

CHARLES T. BRADY, OF DETROIT, MICHIGAN.

EXAMINATION LAMP.

Application filed May 31, 1927. Serial No. 195,571.

The present invention pertains to a novel lamp constructed for use in examination of objects such as parts of the body, documents, finger prints and the like.

5 The principal object of the invention is to provide a device of this character for throwing a restricted area of light on the object under examination and for promptly and rapidly enlarging this area to a full flood when desired.

10 In the accomplishment of these objects, the lamp housing is fitted with a lens in one of the walls thereof, and over this lens is fitted a hinged cover having an aperture for 15 reducing the diameter of the light shaft. The hinge connection between the cover and the housing includes a spring tending normally to remove the cover from the lens, and a latch is provided for retaining the 20 cover over the lens. When it is desired to convert the restricted area of light into a full flood, the latch is released and the spring in the hinge quickly moves the cover away from the lens.

25 The cover is also adapted to support additional light-modifying devices on the outer surface thereof. One of these devices, for example, includes a tube containing a slideable condensing lens and a fixed focusing lens, so that the intensity of the light projected upon the object may be varied at will.

30 The invention is fully disclosed by way of example in the following description and in the accompanying drawings, in which—

35 Figure 1 is a side elevation of the device; Fig. 2 is a front view thereof;

Fig. 3 is a section on the line 3—3 of Figure 2;

40 Fig. 4 is a front elevation showing a modified form of lens support secured to the device; and

Fig. 5 is a section on the line 5—5 of Figure 4.

45 Reference to these views will now be made by use of like characters which are employed to designate corresponding parts throughout.

50 The numeral 1 represents a suitable pedestal having a lamp socket 2 mounted on the upper end thereof. A U-shaped member 3 formed of a thin strip of metal is fixed to the upper end of the member 1 and supports a lamp housing 4 having in its bottom an opening 5 enclosing the socket in such a manner that the latter is not engaged by any part of the housing. This arrangement

reduces the conduction of heat from the housing to the socket, and conduction occurs only through the comparatively thin member 3 so that its effect is negligible. 60 The housing contains a lamp 6 fitted in the socket and is formed with vents 7 in the upper part thereof.

65 The forward end of the housing is open and is fitted with a lens frame 8 held in place by screws 9. A lens 10 is inserted in the frame and locked therein by clips 11 secured to a side of the frame as clearly shown in Figure 3.

70 To the lens frame is applied a door frame 12 which is supported by hooked members 13 extending inwardly therefrom and engaging studs 14 on the lens frame. The door frame is formed at one side with a pair of ears 15 and is equipped with a door 16 having also 75 a pair of lateral ears 17 aligning with the ears 15. A hinge pin 18 is passed through both sets of ears and is surrounded by a spring 19 having one end 20 bearing against the door frame and the other end extended 80 at 21 into engagement with the door whereby normally to hold the latter in open position. The door is however held in closed position by a spring latch 22 carried by the door frame.

85 The door 16 has a threaded aperture 23 preferably concentric with the lens 10. Into this aperture is screwed a tube 24 which reduces the shaft of light to a suitable diameter. When it is desired to have a 90 flood of light rather than a restricted circle, the latch 22 is moved away from the door, and the door is rapidly swung open by the action of the spring 18.

95 In Figures 4 and 5 is illustrated a construction wherein the light tube 24 is replaced by a set of lenses for further modifying or concentrating the light passed through the lens 10. This device includes a bell 25 from which extends a tube 26. The bell has a flange 27 formed with bayonet slots 28 and 29 adapted to engage studs 30 carried by the door 16 for supporting the device. The slot 29 is elongated as shown in Figure 4 in order to accommodate the latch 22. A lens holder 31 is slidably mounted in the tube 26 and contains a condensing lens 32 in line with the aperture 23. In the forward end of the tube 26 is fitted a focusing lens 33. It will be apparent that the holder 31 may be conveniently adjusted in the tube 26 either prior to the application 100 105 110

of the device to the studs 30 or subsequently by means of an object passed through the aperture 23 while the door is in open position.

5 Although a specific embodiment of the invention has been illustrated and described, it will be understood that various alterations in the details of construction may be made without departing from the scope of the invention as indicated by the appended claim.

10 What I claim is:—

A light comprising a lamp housing, a lens

in a wall thereof, an apertured cover movably applied to said wall and adapted to overlie said lens, a hinge joining said cover to said housing, said hinge including a spring tending to move the cover away from said lens, and a latch for maintaining said cover over said lens, said cover being adapted to support a light-modifying device 15 around the aperture thereof. 20

In testimony whereof I affix my signature.

CHARLES T. BRADY.
